UNITED STATES PATENT OFFICE.

HOMER F. CASEY, OF RAMSEY, ILLINOIS.

BROODER.

Application filed August 13, 1923. Serial No. 657,190.

This invention relates to poultry brooders and it consists in the novel features hereinafter described and claimed.

An object of the invention is to provide a brooder having a hover chamber with a heater located therein and means for regulating the heater whereby the interior of the hover is kept at a desired degree of temperature.

10 In the accompanying drawings:

Figure 1 is a side elevational view of the brooder with a portion of the wall of the hover chamber broken away.

Figure 2 is a top plan view of the brooder.

15 Figure 3 is a vertical transverse sectional view thereof.

Figure 4 is a fragmentary horizontal sectional view cut on the line 4—4 of Figure 3.

20 Figure 5 is a similar sectional view cut on the line 5—5 of Figure 3, and

Figure 6 is an enlarged fragmentary sectional view through the lower portion of the heater of the brooder.

The brooder includes a heater body 1 which is closed at its upper end by a cover 5 having a handle 6. A fire box 2 is located in the lower portion of the heater body 1 and a grate 3 is located therein and ash pit 4 is provided below the grate. The 25 grate is supported upon a frame 3' which is connected with a shooter member 8 and the shooter member is connected with a handle member 8' which passes through the sides of the ash pit. The ash pit is provided with a door 7. A flue pipe 9 connects with the interior of the heater body 1 through the sides thereof and a smoke pipe 10 is mounted upon the flue pipe. The end of the flue pipe 9 is normally closed by the 30 cap 11. The flue pipe 9 is provided at its upper side with tubular extension 12 over which is located a damper 13.

The hover chamber includes a top wall 14 having a central opening 15 which receives the body 1 of the heater. The plate 14 is provided with a downwardly disposed periphery of flange 16 to which is attached a curtain 17. Suitable brace rods or members 18 are disposed between the plates 14 and the upper portion of the heater body 15.

1. The smoke pipe 10 hereinbefore mentioned passes through an opening 19 provided in the plate 14.

An angularly shaped pipe 20 passes through the sections of the fire box and the heater body at a point below the grate 3. An arm 22 is mounted upon the pipe 20 and an L-shaped arm 21 is pivotally connected with the arm 22 and lies under the same or in the same vertical plane. Thermostat devices 23 and 24 are interposed between the arms 21 and 22. A second L-shaped arm 26 is mounted upon the arm 21 and passes through the arm 22 as best shown in Figure 3 of the drawings. A valve 25 is adjustably mounted upon the arm 26 and is disposed above the upper or outer end of the pipe 20. The arm 27 is connected at one end of the arm 21 and at its other end is connected with an extension 28 of the damper 13. Thus it will be seen that when the temperature in the hover reaches a certain degree the action of the thermostat 23 and 24 will cause the valve 25 to seat upon the upper end of the pipe 20, thereby cutting off the supply of air to the fire box and below the grate 3. At the same time the damper 13 is controlled through the medium of the rod 27 and the relative movement of the arm 21.

What is claimed is:

A device of the class described, the combination with a heater and a chamber surrounding the same; of an air inlet pipe mounted in the lower portion of said heater below the fire box and having its outer end disposed within said chamber, and means for automatically controlling the flow of air to said pipe, comprising an arm projecting laterally from the outer end of said pipe, an additional L-shaped arm pivotally secured at one end to the outer end of the first-mentioned arm and arranged in the same vertical plane of the latter therebelow, complementary thermostatic elements carried by said arms, a spring connecting said arms, the first-mentioned arm being provided with an opening adjacent its inner end, an L-shaped projection carried on the L-shaped arm and having one arm projecting through the opening in the first-mentioned arm, a valve 100

adjustably supported on the outer end of the L-shaped projection and disposed above the outer end of said pipe to open and close the latter, a flue pipe projecting laterally from said heater and disposed within said chamber, a damper arranged in the length of said flue pipe, and an adjustable rod connecting said damper with the aforesaid L-shaped arm as and for the purposes described.

10

In testimony whereof I affix my signature.

HOMER F. CASEY.
